UNITED STATES PATENT OFFICE

2,108,022

TUBE OF THERMOPLASTIC DERIVATIVES
OF CELLULOSE

William Salemme, West Orange, N. J., assignor to
Celluloid Corporation, a corporation of New Jersey

Original application May 24, 1934, Serial No. 727,-
210. Divided and this application July 8, 1936,
Serial No. 89,549

9 Claims. (Cl. 120—42)

This invention relates to tubes such as fountain pen and pencil barrels, wire conduits, etc. and to cylindrical tubes for blowing into irregular shaped articles such as brush handles, etc., that 5 contain a thermoplastic composition which may comprise a derivative of cellulose with or without a plasticizer.

This application is a division of my application S. No. 727,210, filed May 24, 1934.

10 An object of the invention is the economic and expeditious production of tubes from thermoplastic derivatives of cellulose. Another object of the invention is the production of tubes having desirable properties heretofore unattainable. 15 Other objects of the invention will appear from the following detailed description.

In the drawings wherein like numbers refer to the same or corresponding elements:

Fig. 1 is a perspective view partly in section 20 of a device constructed according to this invention.

Fig. 2 is a perspective view of a device for cementing the edges of a formed tube.

Fig. 3 is a perspective view of a sheet of material containing a window strip.

Fig. 4 is a perspective view of a tube formed according to this invention and containing the window strip.

Fig. 5 is a perspective view of a sheet having 30 angled sides for obtaining a "butt" joint in the formed tube when working with heavy or thick material.

Fig. 6 is an end view of a tube formed of a sheet having angled edges.

35 Fig. 7 is a perspective view of a thin sheet having right angled edges.

Fig. 8 is an end view of a tube formed from a sheet as shown in Fig. 7.

Fig. 9 is a side view of an optional shaping 40 member to be used in the device shown in Fig. 1.

Fig. 10 is an end view of the shaping member shown in Fig. 9.

Tubes from thermoplastic derivatives of cellulose or cellulose derivatives made more thermoplastic by means of plasticizers have been made by molding the same in dies, winding a sheet in roll form on a mandrel while immersed in a solvent bath, by spirally winding a strip on a 50 mandrel and by extrusion, all of which require a skilled operator and are cumbersome. This invention, however, is much simpler and is capable of producing effects in the finished articles not heretofore attainable. Thus, this invention renders possible many configurations which could

not be obtained before with rod stock, sheet stock, by the extrusion or casting methods.

The spiral tube was not satisfactory for certain purposes on account of the spiral seam. A straight line or lateral seam is less conspicuous, 5 but the molding methods generally prescribed for accomplishing this are not practical or feasible. The fins of the two molded seams have to be scraped off, smoothed and the joint is often times quite weak, owing to the lack of cement 10 during the molding operation. The molded seams also show a strained condition which manifests itself in unevenness when the tube is subjected to any high temperatures, such as hot water. When molded articles from which the 15 fins have been scraped are immersed in hot water, there is a tendency for the tube to collapse which reveals the strained condition. In the case of spiral tubing it is necessary to apply uniform tension or twist to insure good welding. The result is that the production of satisfactory tubing 20 depends almost entirely upon the operator's technique. This invention is less subject to the personal element. It makes a very strong tube, which can be demonstrated by the fact that a 25 tapered steel mandrel hammered into the tube fails to pry it open and also by the fact that the tube may be immersed in boiling water for long periods of time without collapsing at the seam. Furthermore, this invention is unlimited in the 30 size of tubes that may be formed. Thus the method can be applied to the manufacture of tubes of from below $\frac{1}{16}$ of an inch in diameter and .0075 inch in gauge to tubes of above $2\frac{1}{2}$ inches in diameter and .25 inch in thickness. 35 Gauge of sheet stock and diameter of tubing are not necessarily dependent on each other. By this invention a small diameter tube may be made of heavy stock and a large diameter tube may be made of thin gauge stock.

According to my invention I cut or form a strip of a thermoplastic material, especially a thermoplastic derivative of cellulose, of the width equal to the circumference of the desired tube. This strip of material is immersed in water or 45 other suitable heating medium until the material is sufficiently soft to readily bend and remain bent without a tendency to spring back to original position. When the thermoplastic strip is sufficiently soft, which ordinarily requires only a few 50 minutes in boiling water, it is drawn by one end, which is preferably tapered and bored, by any suitable means such as by a strong wire, and pulled steadily through a cold water jacketed metal tube whose diameter and internal configu- 55

ration is varied according to the size and shape of the tube desired. In making tubes of heavy gauge strips, the sides of the strips are preferably cut at an angle or scarfed to form a full edge to edge abutment when twisted to a tube shaped article. Owing to the total immersion of the strip in hot water there is no stress or strain along the edges. After forming, the tubes are dried and may then be cemented by immersing, 5 or at least immersing the seam of, the tube lengthwise in a trough bath filled with a solvent for the material and opening the seam with a blade to insure the penetration of the solvent into the seam. Instead of a solvent any other 10 adhesive agent may be employed. The formed tube may then be allowed to dry and may be subjected to any of the finishing operations such as straightening and/or stretching over a mandrel, drawing and grinding. The drawing operation 15 20 may be merely redrawing the tube through a device similar to the one in which it was formed or the tube may be stretched over a mandrel, the loaded mandrel being inserted in a container, pipe, etc. through which steam is circulated to 25 render the tube soft. The tube and mandrel are then pulled through a cold water jacketed tube of a diameter less than the formed tube after which the tube is removed from the mandrel.

The stretching operation may be performed in 30 a similar device to the tube forming device. That is, the softened tube is drawn through a cold metallic tube of a diameter less than that of the formed tube. This stretching operation is also applicable to the smoothing out and reducing the 35 diameter of solid rods which are softened with heat and pulled through the cold jacketed cylinder in the same manner as the tubes.

Further according to my invention I construct a device that is efficient and is both simple to 40 make and use, which device in part resembles an ordinary laboratory condenser with the ends of the tube cut off near the jacketed portion. There may also be provided a bath or oven or other means of supplying the necessary heat to soften 45 the thermoplastic material and a second bath for cementing the formed seams. Any suitable means may be used for drawing the tubes through the jacketed shaping cylinder.

All parts of the device that come in contact 50 with the thermoplastic material or the reagents used therewith, such as the bath containers, the shaping cylinder, etc., may be made from stainless steel or steel coated with a protective alloy or metal such as chromium, nickel and the like.

55 Any suitable thermoplastic material may be shaped to a tube by this invention. The thermoplastic derivatives of cellulose, however, lend themselves especially well. Under the term thermoplastic derivative of cellulose may be included cellulose nitrate, organic esters of cellulose, cellulose ethers and the mixed ethers and/or esters of cellulose. Examples of organic esters of cellulose are cellulose acetate, cellulose formate, cellulose propionate and cellulose 60 butyrate, while examples of cellulose ethers are ethyl cellulose, methyl cellulose and benzyl cellulose. Such mixed esters may be employed as the nitro cellulose acetate. Also mixtures of two or 65 more derivatives of cellulose may be employed in the same plastic material, for example a mixture of cellulose acetate and cellulose nitrate.

The cellulose derivative may contain plasticizers to make them more readily susceptible to the action of heat. The plasticizer may be any 70 suitable one for the particular cellulose deriva-

tive or mixture of cellulose derivatives employed. The plasticizers may be any of the high boiling solvents or softening agents as, for example, the aryl sulphonamides such as para ethyl toluol sulphonamide, the alkyl phthalates such as dimethyl phthalate, the dialkyl tartrates such as dibutyl tartrate, the alkoxy esters of polybasic organic acids such as diethyoxy ethyl phthalate, the polybasic acid esters of the mono alkyl ethers of polyhydric alcohols such as diethylene glycol 10 ethyl ether ester of phthalic acid, the alkyl esters of phosphoric acid such as triethyl glycol phosphate, the aryl esters of phosphoric acid such as tricresyl phosphate, the mixed alkyl and aryl phosphates, and camphor. The plasticizers may 15 be used alone or in combination with others. The quantity of plasticizers employed may vary within very great limits, say, from 10 to 75 parts by weight per 100 parts of the cellulose derivative 20 in the finished product.

The plastic material may contain besides the derivative of cellulose and plasticizer, effect materials such as pigments, filling materials, soluble or insoluble dyes or lakes, fire retardants, sizes and oily materials. Examples of pigments and 25 filling materials are metallic salts and oxides such as titanium oxide, zinc oxide, mercurous chloride, bismuth oxy chloride, powdered metal such as powdered aluminum and bronze, powdered non-metallic substances such as logwood, lampblack 30 and fish scale. Examples of fire retardants are beta chlorophthalene, triphenyl phosphate and tricresyl phosphate. Examples of sizes are the waxes, resins and synthetic resinous material. Examples of the oily materials are the animal, 35 vegetable and mineral oils such as castor oil, olive oil, neat's foot oil and petroleum jelly, glycerine, glycols and the derivatives and substitution products of the polyhydric alcohols.

The strips of thermoplastic material may be 40 cut from any suitable sheets or slabs. The strips may be transparent, translucent or opaque and may be colorless or may have any suitable pigment, dye or effect material incorporated therein to produce mottled, variegated or other differential effects or pearl-like or nacreous appearance. Instead of using stock entirely of the same material, there may be used composited or 45 laminated plastic sheets, making it possible to obtain various artistic effects, such as pearl, cloisonné, snakeskin and the like, which cannot be obtained in any other manner. This modification also makes it possible to use as base stock, materials which would be unsuitable for surface effects because of color or inferiority of stock, 50 but which, by means of overlays, can be made to 55 present an agreeable surface or color.

The composite sheets or strips for use in making tubes in accordance with the present invention may be produced in any suitable manner. 60 For example, a pearl, onyx or any suitably colored or patterned effect is veneered with a sheet of colored or colorless transparent nitrocellulose, cellulose acetate or other cellulose derivative so that in the subsequent operations the transparent 65 sheet will protect the under-layer containing the pattern or color effect. Also a transparent sheet of about 20 one thousandths of an inch may be composited over a fabric containing a design and a base sheet of material of any color to make up 70 a total thickness of 60 one thousandths of an inch. The fabric may be replaced by a lithographed thin sheet or by a celluloid or similar sheet previously impressed with a finish such as morocco or snakeskin. Further, the sheets and 75

slabs may be formed by any other suitable process as more fully described in U. S. Patents Nos. 1,864,794 issued June 28, 1932; 1,812,283 issued June 30, 1931; 1,814,641 issued July 14, 1931; 5 1,845,457 issued February 16, 1932; 1,899,053 issued February 28, 1933; 1,920,118 issued July 25, 1933; and 2,054,848 issued September 22, 1936.

The strips 10 of suitable width, thickness and 10 length are tapered at one end as shown at 11 in Fig. 1. They are then placed in a tank 12 containing a liquid 13 that has little or no chemical action on the thermoplastic derivative or other ingredients of the strip material. The liquid may be water or other suitable liquid. Means, not 15 shown, such as an electric resistance or inductance coil, steam coil, open flame or other means may be employed for raising and maintaining the liquid at an elevated temperature, which temperature will depend upon the softening temperature 20 of the thermoplastic material.

The strip material after being softened is attached, as by a hook 14, a tong member, or other gripping element, to a cable 15 or other suitable drawing element. The cable or drawing member 25 is then caused to pull the strip through a metal tube 16 that is cooled by a fluid flowing through a space formed by a jacket 17 surrounding the tube 16. The jacket is preferably insulated with a coating of asbestos 18, cork or other suitable 30 coating and is equipped with an entrance 19 and exit 20 for circulating within the space between the jacket and the tube 16 a cold fluid that may be water, brine or other suitable cooling agent. The cable or drawing member 15 may be caused 35 to exert an even pull on the strip by winding said cable on a roller 21 by means of the hand crank 22, which in working on long strips, may be supplanted by an electric motor or other suitable source of positive power, or by a weight attached to one end of the cable which is passed over a pulley.

The metallic shaping tube 16 may be tapered or funnel shape for a short distance at the entrance and to permit easy threading of the cable and strip thereto. The tapered part is preferably 45 short such that the material is immediately chilled as soon as it has reached its desired shape. The shaping tube may be round in cross section as shown in Fig. 1, or it may be elliptical, square, 50 polygonal, heart shape, etc. If desired, tubes with more elaborate cross sections may be formed by employing a shaping tube, as shown in Figs. 9 and 10, which is round at the entrance end 23 and any suitable shape at the exit end 24, for 55 example, star shaped.

After the strip material is formed into a tube, it may be submerged in a solvent bath 25 contained in a suitable trough 26 having means 27 for holding the tapered end 11 of the tube. 60 While the tube is submerged in the solvent, a blade 28 may be drawn along the tube to momentarily open the seam and allow the abutting edges of the thermoplastic derivative to come in contact with the solvent. The blade is easily inserted 65 in the seam by reason of the tapered end 11 of the tube. The tube, being set and free of stresses and strains due to its method of formation closes tightly together again at the rear of the blade. Instead of employing a solvent bath, 70 there may be employed an adhesive in the form of a liquid or paste which may be applied onto the edges immediately back of the blade. When employing a solvent bath, the tube upon springing back to closed position, after the passing of 75 the blade, forms a perfect weld which upon drying

becomes as stout as the remaining part of the tube.

After treatment in the solvent liquid or cementing material, the tube may be seasoned in a normal manner. Examples of suitable solvent 5 material are chloroform, acetone, a mixture of acetone and ethyl or methyl alcohol, ethylene dichloride, a mixture of ethylene dichloride and ethyl or methyl alcohol, and a mixture of methyl chloride and ethyl or methyl alcohol. Examples 10 of cementing materials that may be applied to the opened edges are solutions of organic derivatives of cellulose, vinyl resin products, cresylic resin products and rubber containing adhesives.

When forming tubes of relatively thin sheets, 15 the sides of the strip may be cut at right angles to the face of the strip, as shown at 39 on Fig. 7, which will form a full radial abutting joint as shown in Fig. 8. However, when forming tubes 20 of relatively thick sheets, the sides of the strip should be scarfed as at 31 on Fig. 5 such that when the strip is curved the full width of the edge will contact with the opposite edge as shown in Fig. 6 in a radial joint.

For tubes that are to contain liquids or powders such as fountain pen barrels, etc., a block 25 may be formed of three layers of differing composition, the middle layer being a clear transparent material. This block is then sliced to form strips used in making tubes. In this way 30 a tube of opaque highly decorative material may be formed that has a transparent window running lengthwise thereof allowing visibility into the tube. Thus, in Fig. 3 is shown a strip composed of two opaque side strips 32 joined by a 35 highly transparent strip 33. When such a strip is formed into a tube the transparent strip forms a window through which the height of material in the tube may be located.

The device may be operated as a single unit 40 or a tank of, say boiling water, may be provided at the ends of a battery of the cold water jacketed shaping types. All the operator has to do is hook the cables through the holes in the tapered ends of the strips and the wires pulled 45 with an even tension by suitable means. The shaping tubes may vary from 6 inches to 2 feet or more in length, depending upon the type and weight of the material worked. It is highly important that the softened, heated thermoplastic 50 strip be immediately cooled as it enters the coolers to prevent any stretching and for preventing the development of stresses. Therefore, it is essential that there be good circulation of cooling fluid surrounding practically the entire 55 length of the tube, particularly at the entrance end.

When making optical tubing it is not necessary to apply cement to close the seam. The optician buys the tubing with open seam, inserts the metal 60 rim or rod and then immerses the entire article in a solvent. The optical tubing thus made is unique and attractive as it may present an over-all pearl or decorative surface not present in stuffed rods. A further method of forming 65 a rod covered article is to feed the metallic rod simultaneously with the strip to the shaping tube such that the thermoplastic strip is wrapped around the metal rod.

Tubes made according to this invention lend 70 themselves admirably to blowing shaped articles or forming operations, making possibly many configurations which are entirely new, particularly for shaving brush handles and like objects. Pearl stripes or laminations and the luster of 75

same are uniform all-around and the seam is very hard to detect. These shaped, blown or tube formations may be used for fountain pens, towel bars, bed stands, golf shafts, broom sticks, 5 billiard cues, etc. or for lining for pipes and tubes and insulation purposes.

The sheet material from which the strips are cut may be laminated sheet stock with or without inlaid material and coloring matter between 10 the sheets. Thus, tubes having fiber or flexible metal inlays may be formed and used to advantage.

The tubes after being formed and their seams sealed may be softened by heat and drawn 15 through a shaping tube of slightly smaller diameter than the tube in which they were formed. By this means there is a drawing action which reduces the diameter of the tube and also smooths out any irregularities on the surface. 20 This action also aids in obliterating any visible seam. Solid extruded rods may also be drawn through such a device to reduce their diameter and smooth their surface thereby eliminating any necessity of grinding and polishing the small 25 rods to obtain a smooth surface of the desired sized rod and to greatly reduce the necessity of grinding seams on large and heavy tubes and rods.

The blown or shaped articles made from the 30 tubes or the tubes themselves may be filled with any suitable filling materials to form solid articles. Likewise, the tubes may be stretched over solid wooden or artificial material cores for umbrella and cane handles, etc.

35 Hollow articles made in accordance with this invention are characterized by the fact that when they are submerged in boiling water for five minutes they are free of collapsing or "caving in" at the seams and undesirable distortions. 40 Moreover, unless they are given a preshrinking treatment, such articles when subjected to boiling water for five minutes shrink appreciably, from 3 to 25%, usually 5 to 15%, in length, due to release of longitudinal stresses set up during 45 the above described stretching operations.

It is to be understood that the foregoing detailed description and drawings are merely given by way of illustration and many alterations may be made therein without departing from the 50 spirit of my invention.

Having described my invention, what I desire to secure by Letters Patent is:

1. A hollow article of thermoplastic material having abutting edges joined in a permanent 55 straight lateral seam, said article being substan-

tially free of residual stresses tending to cause undesirable distortion and collapsing.

2. A hollow article of thermoplastic derivative of cellulose having abutting edges joined in a permanent straight lateral seam, said article 5 being substantially free of residual stresses tending to cause undesirable distortion and collapsing.

3. A hollow article of thermoplastic material having abutting edges joined in a permanent 10 straight lateral seam and being transparent in at least a portion thereof, said article being substantially free of residual stresses tending to cause undesirable distortion and collapsing.

4. Fountain pen barrels and the like of thermoplastic material having abutting edges joined in a permanent straight lateral seam, said article being substantially free of residual stresses tending to cause undesirable distortion and collapsing. 15

5. Fountain pen barrels and the like of thermoplastic derivative of cellulose having abutting edges joined in a permanent straight lateral seam, said article being substantially free of residual stresses tending to cause undesirable distortion and collapsing. 20

6. A hollow article of thermoplastic material having abutting edges joined in a permanent straight lateral seam, said article being substantially free of residual stresses tending to 30 cause undesirable distortion and collapsing and having residual stresses tending to shorten the length thereof.

7. A hollow article of thermoplastic derivative of cellulose having abutting edges joined in a permanent straight lateral seam, said article being substantially free of residual stresses tending to 35 cause undesirable distortion and collapsing and having residual stresses tending to shorten the length thereof.

8. Fountain pen barrels and the like of thermoplastic material having abutting edges joined in a permanent straight lateral seam, said article being substantially free of residual stresses tending to cause undesirable distortion and collapsing. 40

9. Fountain pen barrels and the like of thermoplastic derivatives of cellulose having abutting edges joined in a permanent straight lateral 50 seam, said article being substantially free of residual stresses tending to cause undesirable distortion and collapsing and having residual stresses tending to shorten the length thereof.

WILLIAM SALEMME. 55
